Primary Examiner — Eric Goodman*Assistant Examiner* — Rachel Voorhies(74) *Attorney, Agent, or Firm* — Banner & Witcoff, Ltd.(57) **CLAIM**

The ornamental design for a display screen with graphical user interface, as shown and described.

DESCRIPTION

FIG. 1 is a front view of a display screen with graphical user interface showing our new design; and,

FIG. 2 is an enlarged view of the display screen with graphical user interface as shown in FIG. 1.

The broken line showing of the display screen, text, and graphic features forms no part of the claimed design.
